CONTROL MECHANISM

Chester Arthur Purdy, Oak Park, Ill., assignor to
Western Electric Company, Incorporated, New
York, N. Y., a corporation of New York

Original application June 22, 1929, Serial No.
372,818, now Patent No. 1,963,381. Divided and
this application March 13, 1934, Serial No.
715,382.

5 Claims. (Cl. 192—142)

This invention relates to a control mechanism, and more particularly to a revolution counter and control mechanism for material winding machines, and is a division of my copending application entitled Condenser winding machine, Serial No. 372,818, filed June 22, 1929 now Patent 1,963,381.

An object of the invention is to provide a simple, inexpensive and efficient mechanism for automatically controlling machine operations.

In accordance with this object, one embodiment of the invention contemplates the provision of a revolution counter and control mechanism for material winding machines, wherein a revolution indicating wheel is driven in synchronism with the winding arbor through an electromagnetic clutch which is automatically actuated to start each operating cycle of the machine. Adjustable contacts carried by the indicating wheel control electrical circuits for controlling various operations of the machine and for effecting the disengagement of the clutch when the indicating wheel arrives at a predetermined indication, whereupon the indicating wheel is automatically returned to its initial or starting position.

Other features and advantages of the invention will become apparent from the following detailed description when read in conjunction with the accompanying drawing, in which

30. Fig. 1 is a vertical sectional view of a revolution counter and control mechanism embodying the features of the invention;

Fig. 2 is a fragmentary plan section taken on line 2—2 of Fig. 1, and

35. Fig. 3 diagrammatically illustrates electrical circuits that may be controlled by the mechanism.

Referring to the drawing, the revolution counter and control mechanism comprises a shaft 10 journaled in a housing or frame 11 and having secured at its upper end a rotatable electromagnet 12 carrying an energizing coil 13 the terminals of which are connected to leaf spring contacts 15 and 16 secured to an insulator 17 fastened to the underside of the electromagnet. The leaf spring contacts 15 and 16 in turn resiliently engage contacts 18 and 19, respectively, which slidably contact with rings 21 and 22, respectively, mounted in a stationary insulator 23

50 and through which the energizing coil 13 is connected to an electrical current supply, such as a battery 24 (Fig. 3). Journaled within a vertical bore 25 of the shaft 10 is a smaller shaft 26, to a shoulder 27 of which an iron disk 28 is resiliently secured by means of a spring disk 29.

The disk 28 is adapted to be attracted and rotated by the electromagnet 12 when it is energized. Thus, the electromagnet 12 and the iron disk 28 constitute the driving and driven members, respectively, of what is essentially an electromagnetic clutch.

The shaft 26 terminates at its upper end in a square shank carrying a suitably calibrated circular member or indicating wheel 30 on the underside of which is secured one end of a torsion spring 32 having its other end secured to a stationary pin 33 projecting from a cover plate 34 fastened to the top of the frame 11. Through the rotation of the indicating wheel 30, energy is stored in the spring 32 so that when the electromagnet 12 is deenergized and the iron disk 28 is retracted therefrom by the spring disk 29, the spring 32 automatically returns the indicating wheel to its initial or starting position where a stop 35 secured to the underside of the indicating wheel engages a stop pin 36 projecting from the upper side of the cover plate 34. Spacer pins 37 project slightly above the upper surface of the electromagnet 12 to prevent sticking of the clutch members when the electromagnet is deenergized.

Carried at the upper end of the shaft 26 is a contacting arm 38 which is frictionally rotatable about the indicating wheel 30 so as to be adjustable angularly with respect thereto. A clamping nut 39 is provided for securing the arm 38 to the indicating wheel in any desired position. The arm 38 is bent in under the indicating wheel where it carries a contact 40 adapted to engage with a contact 41 mounted in an insulator 42 of the cover plate 34. The contacts 40 and 41 may be arranged to control electrical circuits for automatically controlling machine operations. For example, when the mechanism is employed in conjunction with a condenser winding machine of the type disclosed in the copending application above referred to, the contacts 40 and 41 may be connected in electrical circuits, one such circuit being illustrated in Fig. 3, for controlling the disengagement of the electromagnetic clutch to permit the indicating wheel to return to its initial position upon arriving at a predetermined indication.

When the mechanism is employed with a winding machine, as mentioned above, the shaft 10 is driven in synchronism with the winding arbor through interconnecting reduction gears or in any other suitable manner (not shown). The indicating wheel 30 may be calibrated to indicate revolutions of the arbor and the contacting arm

38 is adjusted so that its contact 40 engages the contact 41 when the winding arbor has completed a predetermined number of revolutions.

While the electromagnet 12 is energized, the indicating wheel 30 is driven by the shaft 10 through the electromagnetic clutch, as described above. An energizing circuit for the electromagnet 12 is shown in Fig. 3, and may be traced as follows: from the grounded battery 24 through conductor 45 the coil 13 of the electromagnet 12, conductor 46, contact 47 and grounded contact disk 48. The contact 47 is designed to make a sliding contact with the periphery of the disk 48 and the latter is carried by a one-revolution shaft 49. The periphery of the disk 48 is completely insulated except for a small portion thereof, whereby the energizing circuit of the electromagnet 12 is maintained closed only while the disk 48 is at rest in its normal position, as shown in Fig. 3. Thus, upon rotation of the disk 48 the electromagnet 12 is de-energized, whereupon the torsion spring 32 automatically returns the indicating wheel to its initial position as described above.

25 Rotation of the shaft 49 may be controlled by any suitable one-revolution clutch 50 under the control of a solenoid 51, the energizing circuit of which may be controlled by the counter contacts 40 and 41. As shown in Fig. 3, the contact 41, 30 when engaged by the contact 40, establishes an energizing circuit for the solenoid 51, which may be traced as follows: from grounded battery 24, through conductor 53, the coil of solenoid 51, conductor 54 and contacts 41 and 40 to ground. 35 Upon being energized, the solenoid 51 causes the actuation of the one-revolution clutch 50 to cause the shaft 49 and contact disk 48 to make one complete revolution and then stop. It is obvious that the shaft 49 may be provided with cams, 40 electrical contacts, or other means for initiating, stopping or otherwise controlling various operations of the machine or for operating various signalling means.

If desired, the indicating wheel 30 may be provided with several adjustable contacting arms similar to the arm 38 and such arms may each be provided with one or more contacts similar to the contact 40 for cooperating with companion contacts similar to the contact 41 to selectively 50 control additional electrical circuits. For example, the arm 38 is shown in the drawing with a second contact 60 adapted to engage a contact 61 in the insulator 42. Also, there is shown in Fig. 1, a second arm 63 similar to arm 38 and carrying a contact 64 adapted to engage a contact 65 in the insulator 42. It is obvious that the additional pairs of contacts 60-61 and 64-65 may readily be employed for controlling additional electrical circuits in the manner illustrated and 60 described in connection with the contacts 40 and 41.

It will be seen that the counter and control mechanism of the present invention is of simple and inexpensive construction and consists of very few parts. The electromagnetic clutch provides a practical driving means for the indicating wheel 5 and the torsion spring provides a simple means for quickly returning the indicating wheel to its initial position. The simplicity of the structure including the electromagnetic drive and the torsion spring provide great flexibility for rendering 10 the mechanism readily adaptable to a large variety of uses.

It is to be understood that the invention is not limited to the particular embodiment thereof herein illustrated and described, except in so far as is defined by the appended claims.

What is claimed is:

1. A control mechanism comprising a movable control member, means for moving said member, said means being capable of assuming two conditions, one in which it is effective for moving said member and the other in which it is ineffective for moving said member, an electrical circuit controlled by said member, and means including a one-revolution clutch controlled by said circuit 25 for controlling said member moving means.

2. A control mechanism comprising a movable control member, means including an electromagnetic clutch for moving said member, an electrical circuit for holding the elements of said clutch 30 engaged, a second electrical circuit, a one-revolution clutch controlled by said second circuit, contacts controlled by said one-revolution clutch for controlling the first mentioned circuit, and contacts controlled by said control member for 35 controlling said second circuit.

3. A counting mechanism comprising a movable indicating member, disengageable means for driving said member, and means controlled by said member for disengaging said driving means 40 and, after a time interval, for again engaging said driving means.

4. A control mechanism comprising a movable control member, means including an electromagnetic clutch for moving said member, an electrical circuit for holding the elements of said clutch 45 engaged, a second electrical circuit, contacts under the control of said control member for controlling said second circuit, and means controlled by said second circuit for controlling the 50 first mentioned circuit.

5. A counting mechanism comprising a movable indicating member, disengageable means for driving said member, yieldable means for disengaging said member from said driving means, 55 electromagnetic means for engaging said member with said driving means, and means under the control of said member for controlling said electromagnetic means.
